UNITED STATES PATENT OFFICE.

WILLIAM P. DUNLAP, OF MAQUOKETA, IOWA.

STATION-INDICATOR.

1,178,303.

Specification of Letters Patent.

Patented Apr. 4, 1916.

Application filed April 1, 1915. Serial No. 18,509.

To all whom it may concern:

Be it known that I, WILLIAM P. DUNLAP, a citizen of the United States, residing at Maquoketa, in the county of Jackson and State of Iowa, have invented certain new and useful Improvements in Station-Indicators; and I do declare the following to be a full, clear, and exact description of the invention, such as will enable others skilled in the art to which it appertains to make and use the same.

My invention relates to improvements in legend displaying devices, such for instance as those used in indicating the names of stations along a railway. The present application, however, relates more particularly to the operating means for practically any preferred type of indicating machine.

The main object of the invention is to provide such operating mechanism employing but two movable parts, namely a reciprocatory operating rod, and an oscillatory lever for actuating the same, the lever being oscillated at intervals by a plurality of trips disposed along the track.

A further object is to so construct the actuating lever as to allow its lower end to be shifted upwardly out of the path of the trips, in case it is necessary to prevent the lever from being operated.

Yet another object is to provide novel means whereby, although a pair of indicating machines are employed, but one of said machines may be operated if desired.

With the foregoing objects in view, the invention resides in certain novel features of construction and combination hereinafter described and particularly pointed out in the claims. In describing the invention, I shall refer to the accompanying drawings wherein like reference characters designate corresponding parts throughout the various views, and wherein;

Figure 1 is a side elevation of a trolley car with parts thereof broken away, showing the application of the invention to use; Fig. 2 is a vertical transverse section through a part of a car equipped with the invention, Fig. 3 is a view similar to Fig. 1, but showing on an enlarged scale one of the indicating devices and the operating means therefor, a portion of the casing of this indicator being broken away to display more particularly the apron therein upon which the names of the various stations are inscribed; Fig. 4 is a view similar to Fig. 3 but illus-

trating the manner in which one end of the operating rods may be disposed to inactive position; Fig. 5 is a perspective view of the operating rod and the lever connected thereto, the lower end of the latter being disposed to inactive position; Fig. 6 is a perspective view of the lower end of the lever illustrating the same swung downwardly to active position; and Fig. 7 is a diagrammatic plan view of a portion of a railway showing another manner in which the trips thereon may be disposed.

In these drawings, constituting a part of the application, a trolley car C is shown as equipped with the usual wheels W which travel upon the rails R, the car being provided with any preferred means of propulsion. Disposed one at each end of the car C in the top thereof, is a pair of legend displaying devices 1 which are considered in the present case as being in the form of station indicators, each of these indicators including a casing 2 which is secured to the car, upper and lower reels 3 and 4 disposed in said casings and operatively connected by any preferred means, an apron 5 wound upon said reels and carrying the names of the various stations, and a toothed operating wheel 6 which is keyed to the shaft of the upper reel 3, whereby partial rotation of the wheels 6 by means yet to be described, will remove the name of the station just passed from view, and will display that of the station being approached. This operation takes place simultaneously in both ends of the car, under normal conditions, although the indicator at one end thereof may be thrown out of action if desired, by construction to be hereinafter explained.

Although the devices 1 are considered in the present application as being station indicators as above set forth, it will be evident that they might be practically any type of legend displaying devices, such for instance as machines for displaying different advertisements successively as the various stations are passed. Furthermore, these devices may be equipped with aprons 5 above described, or may include card or sign dropping mechanism to be successively operated.

Disposed longitudinally within the top of the car C is a horizontal reciprocatory rod 7 which is here shown as formed of a trio of sections, the two endmost sections 8 being pivotally connected at 9 to the central section 10 and being designed at their outer

ends to provide dogs 11 which engage the toothed operating wheel 6 of the indicators 1. It will thus be evident that when the rod 7 is shifted in one direction, one of these indicators will be operated, while the return of said rod to normal position will now operate the other indicator and, since this shifting takes place immediately after passing one station, the name of that being approached is displayed to the occupants of the car.

For the purpose of intermittently reciprocating the rod 7, an upright operating lever 12 is provided, this lever being shown in the present case as disposed at one side of the car, as is likewise the rod 7. The lever 12 is fulcrumed between its ends at 13 to an appropriate part of the car, is pivotally connected at its upper end to the intermediate portion of the central rod section 10 as seen at 14, and is provided with a vertically shiftable lower end 15 which normally projects beneath the car in the path of a plurality of trips 16 disposed directly inside of one of the rails R, it being therefore evident that as the car is propelled over the railway, the end 15 of the lever will strike the trips 16, thus oscillating said lever and changing the legends displayed by the indicating machines 1, it being understood that the trips 16 are disposed at proper points in relation to the numerous stations,

It often happens that it is desirous to run a car along a railway, without carrying passengers thereon, in which case it is useless to operate the indicators 1. The upwardly shiftable lower end 15 of the lever 12 may then be moved upwardly to inactive position as shown in Fig. 5, thus disposing it at such a point as to prevent contact with the trip 16. Although any preferred type of upwardly shiftable lower end could be provided on the lever 12, this end is preferably in the form of a bar pivoted between its ends at 17 to said lever, said bar being normally swung to an upright position and embraced by a sleeve 18, which is slideable on the lever 12 as shown in Fig. 6. When, however, it is necessary to dispose the bar 15 to inactive position, the sleeve 18 is raised and said bar is swung to a horizontal position, whereupon the sleeve 18 is shifted downwardly on the lever into contact with the upper edge of said bar as shown in Fig. 5. It will thus be seen that the bar will be held in its adjusted position and that it is impossible for the lever to be oscillated by the trips 16.

It also becomes expedient, when the device is employed with certain types of cars, to provide means whereby but one of the indicators 1 will be actuated, this device being preferably the one at the front end of the car, since operation of that in the rear end thereof, would be practically useless.

In order to prevent the rod 7 from actuating

both of these indicators, a pair of shiftable levers 19 are preferably provided for raising and lowering the two end sections 8 of said rod, it being evident that such levers may be of any preferred construction for accomplishing the best results. Furthermore, it will be evident that any other type of shiftable member could well be provided for accomplishing the desired end, such details being unimportant.

In the foregoing I have mentioned a plurality of trips 16, and although such trips may be of any preferred formation, they are preferably in the form of metal blocks having notches 16^a in which the rails R rest. By this construction, the trips are rigidly held in their proper positions to be engaged by the lower end of the lever 12. It will be evident, however, that should it be desirable to dispose this lever at the center of the car rather than at one side thereof, the trip blocks must necessarily be disposed at the center of the railway as seen at 16^b in Fig. 7, in which position they are rigidly secured by stakes or the like 16^c driven therethrough and into the road bed. Needless to say, however, I do not wish to be limited to the specific construction of the trip blocks, or to any one positioning thereof, since such features are immaterial.

From the foregoing description, taken in connection with the accompanying drawings, it will be evident that although extremely simple construction has been provided for carrying out the objects of the invention, the same will be very efficient in operation and will possess a number of highly advantageous features.

I claim:

1. The combination with a railway car, of a reciprocatory rod disposed longitudinally in the top thereof, an upright oscillatory actuating lever pivotally connected to said rod and having its lower end disposed beneath the car, trips independent of the car and disposed in the path of the lower end of the lever, and a legend displaying device intermittently actuated by the aforesaid reciprocatory rod.

2. The combination with a railway car, of a reciprocatory rod disposed longitudinally in the top thereof, an upright oscillatory actuating lever pivotally connected to the intermediate portion of said rod and having its lower end disposed beneath the car, trips independent of the car disposed in the path of the lower end of the lever, and a pair of legend displaying devices actuated intermittently by the aforesaid reciprocatory rod and disposed one at each end thereof.

3. The combination with a railway car, of a reciprocatory rod disposed longitudinally in the top thereof and formed of a trio of pivotally connected sections, an up-

right oscillatory actuating lever pivoted to the central section of the rod and having its lower end extended below the car, trips independent of the car and disposed in the path of the lower end of the lever, and a pair of legend displaying devices disposed one at the outer end of each of the end sections of the rod and intermittently actuated thereby.

- 10 4. The combination with a railway car, of a reciprocating rod disposed longitudinally in the top thereof and formed of a trio of pivotally connected sections, an upright oscillatory actuating lever pivoted 15 to the central section of the rod and having its lower end extended below the car, trips

independent of the car and disposed in the path of the lower end of the lever, a pair of legend displaying devices disposed one at the outer end of each of the endmost rod sections and having toothed operating wheels engaged thereby, and a shiftable member for disengaging one of said endmost rod sections from its respective operating wheel.

In testimony whereof I have hereunto set my hand in presence of two subscribing witnesses.

WILLIAM P. DUNLAP.
